(57) **CLAIM**

The ornamental design for a drink bottle lid, as shown and described.

DESCRIPTION

FIG. 1. is a front perspective view of the front, right, and top sides of a drink bottle lid showing our new design;

FIG. 2. is a rear perspective view of the rear, left, and bottom sides thereof;

FIG. 3. is a front view thereof;

FIG. 4. is a rear view thereof;

FIG. 5. is a left side view thereof;

FIG. 6. is a top plan view thereof; and,

FIG. 7. is a bottom view thereof.

The broken lines shown represent unclaimed subject matter of the drink bottle lid and form no part of the claimed design. The dash-dot lines represent the boundary between the claimed design and unclaimed design and form no part of the claimed design.
